Filed May 24, 1962, Ser. No. 70,258

Term of patent 7 years

(Cl. D29—23)

FIG. 1 is a side elevational view of a trophy figurine embodying our new design;

FIG. 2 is a front end elevational view thereof;

FIG. 3 is a top plan view thereof with the broken line showing of the horse omitted for convenience of illustration;

FIG. 4 is a bottom plan view of the trophy figurine; and

FIG. 5 is a rear end elevational view with the broken line showing of the horse omitted for convenience of illustration.

The side not shown is substantially the same as the side shown.

The essential features of our design reside in the portions shown in solid lines.

We claim:

The ornamental design for a trophy figurine, substantially as shown and described.
